Fig. 4

FIGURE 1 is an enlarged transverse sectional view of my design for an extruded form for holding a narrow panel edge.

FIGURE 2 is a plan view of a reach of the extruded form as taken from the indicated arrow 2 at FIG. 1, but on a reduced scale.

FIGURE 3 is a front elevational view of a reach of the extruded form as taken from the indicated arrow 3 at FIG. 1, but on a reduced scale.

FIGURE 4 is a rear elevational view of a reach of the extruded form as taken from the indicated arrow 4 at FIG. 1.

The right end of the form is shown fragmentarily to indicate an article of indefinite length.

I claim:

The ornamental design for an extruded form for holding a narrow panel edge, as shown and described.
